J. G. A.

Fig. 5.

Fig. 1 is a perspective view of a prefabricated bathroom unit embodying my new design as seen from one end with a portion of the wall and ceiling broken away for purposes of illustration;

Fig. 2 is a perspective view thereof as seen from the opposite end with a portion of the ceiling broken away for purposes of illustration;

Fig. 2A is a perspective view of the complete article on a smaller scale;

Fig. 3 is a horizontal midsectional view thereof;

Fig. 4 is a vertical sectional view thereof taken on lines 4—4 of Fig. 3; and

Fig. 5 is a vertical sectional view of the same taken on lines 5—5 of Fig. 3.

I claim:

The ornamental design for a prefabricated bathroom unit, as shown.
